INVENTOR.

Julian Kennedy
Behrweiss, Beymer, Kennedy
His Allies

UNITED STATES PATENT OFFICE.

JULIAN KENNEDY, OF PITTSBURGH, PENNSYLVANIA.

BLAST FURNACE.

Application filed January 26, 1921. Serial No. 440,083.

To all whom it may concern:

Be it known that I, JULIAN KENNEDY, residing at Pittsburgh, in the county of Allegheny and State of Pennsylvania, have invented a new and useful Improvement in Blast Furnaces, of which the following is a full, clear, and exact description, reference being had to the accompanying drawings, forming part of this specification, in which—

10 Figure 1 is a front elevation of a portion of a blast furnace showing the iron notch of the furnace and having my invention applied thereto;

15 Figure 2 is a transverse vertical section of the parts shown in Figure 1;

Figure 3 is a section on the line III—III of Figure 1;

20 Figures 4 and 5 are longitudinal sections taken in planes at right angles to each other of one of the notch wall coolers.

25 My invention has relation to blast furnaces, and more particularly to that portion of a blast furnace which contains the usual iron notch through which the molten iron is discharged from the hearth of the furnace. The wall of the furnace adjacent to and surrounding the notch has usually been protected by means of a cooling plate having 30 means for circulating a cooling fluid therethrough. This plate has, however, proved insufficient in practice to prevent the cutting away of the hearth wall adjacent to the notch, such wall being of a thickness too great to permit it to be efficiently cooled by 35 the cooling action of the said external cooling plate.

40 My invention is designed to provide supplemental cooling means which will be effective in protecting the portion of the hearth wall of the furnace above the iron notch, and where the cutting is most severe, owing to the intense heat in the hearth of the furnace and to the action of the furnace tuyeres.

45 The nature of my invention will be best understood by reference to the accompanying drawings, in which I have shown a preferred embodiment thereof and which will now be described, it being premised, however, that various changes can be made in the 50 details of construction, arrangement and combination of the various parts, without departing from the spirit and scope of my invention as defined in the appended claims.

55 In these drawings, the numeral 2 designates a portion of the hearth wall of a blast

furnace stack. 3 designates the usual iron notch. 4 is the usual cooling plate surrounding said notch and provided with water-circulating pipes 5; and 6 designates some of the usual bosh plate coolers which are inserted in the bosh wall of the furnace above the hearth.

60 In accordance with my invention, I provide a supplemental cooler or coolers which are arranged between the iron notch and the bosh plate coolers, two of the supplemental coolers being shown in the drawings. Each of these coolers consists of a box 7, preferably somewhat wedge-shaped in cross section, to facilitate its insertion and removal. 65 This box is provided with water-circulating connections 8. The boxes are inserted into the hearth wall at a point adjacent to the upper end of the cooling plate 4, extending downwardly and inwardly into said wall in 70 the direction of the iron notch. The exact angle of these plates, together with the extent of their downward projection, may be varied at will. The upper end portions of the plates preferably project outwardly into 75 accessible positions, being provided with suitable eyes 9, to facilitate their removal. The box is preferably provided with an interior baffle wall 10, which is so placed as to cause the cold water entering the box to 80 pass downwardly to a point near the lower end of the box, before escaping into the main chamber of the box. Preferably, this baffle wall will be provided with one or more 85 small openings 11 at its extreme upper portion, so as to permit of the escape of any steam which may be formed at the incoming side of the baffle and permit this steam to readily pass away through the offtake 90 circulating pipe.

95 Usually two of the supplemental coolers, arranged as described, one at each side of the vertical center line of the iron notch, would be sufficient, but I do not desire to limit myself in this respect, as any desired number 100 of these plates may be used. The size and construction may also be changed. It will be noted that by the location of the plates as shown and described, the circulating connections are brought well away from the iron 105 notch, so that they are not exposed to intense heat when the furnace is tapped and are also at a sufficient distance to be protected against hot metal splashing thereon. At the same time, the coolers are brought 110

into that portion of the hearth wall where the cutting action is most severe and where they are the most effective.

I claim:

- 5 1. The combination with a blast furnace having an iron notch, of a cooler seated in the wall of the furnace directly above and adjacent said notch, and a supplemental cooler seated in said wall intermediate said 10 first-mentioned cooler and notch, said supplemental cooler being slightly to one side of the vertical plane of said notch and extending obliquely downward toward the notch, substantially as described.
- 15 2. The combination with a blast furnace having an iron notch, of a cooler seated in the wall of the furnace directly above and adjacent said notch, and a pair of supplemental coolers seated in said wall intermediate 20 said first-mentioned cooler and notch, said supplemental coolers being arranged on opposite sides of the vertical plane of said notch and extending obliquely downward toward the notch, substantially as described.
- 25 3. The combination with a blast furnace having an iron notch and an external cooling plate surrounding said notch, of a cooling member inserted in the wall of the furnace adjacent the upper edge of said plate and directly above said notch, and a supplemental cooling member seated in said 30 wall intermediate said first-mentioned cooling member and notch, said supplemental cooling member being slightly to one side 35 of the vertical plane of said notch, substantially as described.
- 40 4. The combination with a blast furnace having an iron notch and an external cooling plate surrounding said notch, of a cooling member inserted in the wall of the furnace adjacent the upper edge of said plate and directly above said notch, and a pair 45 of supplemental cooling members seated in said wall intermediate said first-mentioned cooling member and notch, said supplemental

cooling members being arranged on opposite sides of the vertical plane of said notch, substantially as described.

5. The combination with a blast furnace, having an iron notch, an external cooling plate surrounding said notch, and bosh coolers above said plate, of supplemental cooling means inserted in the hearth wall of the furnace at a point adjacent to the upper edge of the cooling plate and between the iron notch and the bosh plate coolers, said supplemental cooling means extending obliquely downward toward the notch, substantially as described. 55

6. The combination with a blast furnace having an iron notch, of an external cooling plate surrounding said notch and supplemental cooling means located in the wall of the furnace above said notch and extending behind said cooling plate, substantially as 60 described. 65

7. The combination with a blast furnace having an iron notch, of an external cooling plate surrounding said notch and supplemental cooling means located in the wall of the furnace above said notch and extending behind said cooling plate, one end of said cooling means projecting outwardly from the furnace and having means for conducting cooling fluid thereto, substantially as 70 described. 75

8. The combination with a blast furnace having an iron notch, of an external cooling plate surrounding said notch and supplemental cooling means located in the wall of the furnace above said notch and extending behind said cooling plate, one end of said cooling means projecting outwardly above the external cooling plate and having means for conducting cooling fluid thereto, substantially as described. 80 85

In testimony whereof I have hereunto set my hand.

JULIAN KENNEDY.
